UNITED STATES PATENT OFFICE.

ADONIRAM KENDALL, OF ERIE, PENNSYLVANIA.

VALVE-GEAR FOR STEAM-ENGINES.

SPECIFICATION forming part of Letters Patent No. 269,678, dated December 26, 1882.

Application filed February 23, 1882. (No model.)

To all whom it may concern:

Be it known that I, ADONIRAM KENDALL, a citizen of the United States, and a resident of Erie, in the county of Erie and State of Pennsylvania, have invented a new and useful Improvement in Valve-Gear for Steam-Engines; and I do hereby declare that the following is a full, clear, and exact description thereof, reference being had to the accompanying drawings, and the letters or figures of reference marked thereon.

My invention relates to the construction of that class of steam-engine governors which are attached to and revolve with the main shaft 15 of the engine and operate directly upon the eccentric and move it diametrically across the shaft.

My invention consists in providing a new and improved construction and arrangement 20 of the parts which operate upon and move the eccentric.

My device is illustrated in the accompanying drawings as follows:

Figure 1 is a perspective view. Fig. 2 is a 25 direct side view. Figs. 3 and 4 show details of construction.

⑤ The construction of my device is as follows:

A is the rim of the frame A', the two forming a band-wheel, which may be used for the 30 driving-pulley. The form of the frame A', which is the web or spider of the pulley, is such as will best accommodate the mechanism by which the eccentric is moved.

C is the main shaft of the engine.

35 D is the eccentric of the engine, and is provided with a slot, d, so that it can move diametrically on the shaft.

All the above parts are common in governors of this class.

40 Connected to or cast solid with the eccentric are arms E E, by which the mechanism which moves the eccentric is connected thereto.

B B are the weights, which move by the centrifugal force generated by the rotation of 45 the device.

B' B' are the arms or levers to which the weights are attached. The arms B' and the weights B are cast in one piece, preferably.

These arms are pivoted at b to the frame A', 50 and their ends are connected by rods B² with

toggles G, which operate upon the eccentric, and therefore as the weights are thrown out or in by the motion of the main shaft the toggles G are moved. These toggles are pivoted at one end to lugs g g on the rim A and at 55 the other end to the arms E E of the eccentric at g' g'.

F F are springs, which resist the centrifugal movement of the weights and draw them in toward the center when the momentum of the 60 engine diminishes. These springs have their fixed bearings on the frame A', and their movable bearings are of course on the arms B'.

H H are suspending-rods, on which the eccentric is mounted. They are pivoted at one 65 end to the rim A and at the other end to the arms E of the eccentric, and as they are of the same length and their positions are identical at each side of the eccentric they will permit the eccentric to move around the shaft 70 sufficiently to give the valve the proper lead, and also compel it to move nearly in a straight line diametrically across the shaft to reverse the movement of the valve. Pins j j, which extend from the eccentric through slots J J in 75 the frame A', are provided with heads on the opposite side of the frame, and thus serve to gib the eccentric, so as to prevent lateral motion. This gibbing may, however, be done at the point where the rods H H are connected 80 with the eccentric-arms.

The weights are provided on their outer sides with recesses a', which receive lugs a on the rim A, and thereby lateral movement of the weights is prevented. (See Fig. 3 for detail of 85 this construction.)

The springs F are mounted on telescoping spools formed of the parts f f'. (See Fig. 4.) To insert the springs they are compressed, and a pin, f², is passed through holes in the parts 90 f f' of the spool, and thus fixed they can be put in place and the pin then be removed.

The operation of my governor as such is precisely the same as others of its class or kind—viz., as the momentum varies the position of 95 the weights changes, and they by their connections change the position of the eccentric diametrically upon the shaft, and thereby vary the cut of the engine.

Individually the operation of my governor is 100

as follows: The position of parts shown in the drawings is that which they occupy when the weights are thrown out so far as to bring the eccentric to the central point, and thereby give the valve no movement. This position is attained only when the engine is running at full speed. Any diminution of this speed, which of course must follow at once, will cause the weights to drop toward the center, because the lessening of the centrifugal force will allow the springs F F to assert themselves. This inward movement of the weights will change the positions of the toggles, and that will move the eccentric. On the arms E of the eccentric are two places for connecting the toggles—viz., g' and g^2 . By changing the toggles to g^2 and putting the long rod B^2 where the short rod B^2 now is and the short one where the long one is the governor will be fitted for an engine running in the opposite direction from the one for which it is now fitted—that is to say, by making the changes indicated, or the reverse, the governor is changed from right to left, or the reverse.

25 What I claim as new is—

1. In a steam-engine governor wherein the position of the eccentric is changed by the movement of the weights, the combination, with said eccentric and weights, of the levers B' B', rods B² B², and toggles G G, substantially as and for the purposes set forth.
2. In a steam-engine governor wherein the position of the eccentric is changed by the centrifugal movement of weights, the combination, with said eccentric and weights, of the arms B' B', rods B² B², toggles G G, and springs F F, substantially as shown.
3. In a steam-engine governor wherein the

position of the eccentric is changed nearly diametrically across the shaft, the combination, 40 with said eccentric, of the hanger-rods H H, whereby a reversing motion and the lead is given to the valve, constructed substantially as shown, and arranged to operate for the purposes mentioned.

45 4. In a steam-engine governor wherein the eccentric is moved diametrically across the shaft by the centrifugal movement of weights, the combination, with said eccentric and said weights, of the levers B' B', rods B² B², toggles G G, and hanger-rods H H, substantially as and for the purposes mentioned.

5. In a steam-engine governor wherein the eccentric is moved diametrically upon the shaft by the centrifugal movement of weights, the combination, with said eccentric and weights, of the hanger rods H H, attached by one end to the rim and by the other to the movable eccentric or plate, of the frame A' and rim A, provided with means, substantially as shown, 60 for gibbing the said eccentric and weights, so as to prevent lateral movement of the same.

6. In a steam-engine governor wherein the eccentric is moved by the centrifugal action of weights, the combination, with said weights, 65 of spiral springs F for counteracting the said weights, which springs are mounted on telescoping spools formed of the parts f f', substantially as and for the purposes set forth.

In testimony that I claim the foregoing I have hereunto set my hand this 20th day of February, 1882.

ADONIRAM KENDALL.
